UNITED STATES PATENT OFFICE.

NICOLAI H. HILLER, OF CARBONDALE, PENNSYLVANIA.

WATER DISTRIBUTOR FOR VERTICAL-TUBE CONDENSERS.

Application filed January 6, 1923. Serial No. 610,998.

To all whom it may concern:

Be it known that I, NICOLAI H. HILLER, a citizen of the United States, and resident of Carbondale, in the county of Lackawanna 5 and State of Pennsylvania, have invented certain new and useful Improvements in Water Distributors for Vertical-Tube Condensers, of which the following is a specification.

10 This invention is an improved device for use in connection with vertical tube condensers or other heat interchangers to control the delivery and distribution of the cooling water or other liquid within the tubes.

15 The main objects of my invention are to secure economy and efficiency in the use of the cooling water by preventing the water from running down the centers of the tubes, and to greatly increase the heat transmitting power by insuring the thorough covering of the tube surface by a thin film of the water.

20 My improved distributor in its preferred form is a tubular member adapted to be 25 detachably supported within the upper open end of a vertical tube of a condenser to partially close the tube, said member having passages for the water to flow into the tube in a diagonal or helical direction directly 30 against and along the tube surface to form the desired film and a uniform distribution. The member also has a large central passage serving as an overflow into the tube in case 35 the water above the upper tube sheet rises above a predetermined level.

In the accompanying drawings I have illustrated one embodiment of my invention.

In these drawings:

Fig. 1 is a vertical section showing a part 40 of a vertical tube condenser equipped with my improved distributor.

Fig. 2 is a side elevation of one of the distributors.

Fig. 3 is an end view of the distributor, 45 and

Fig. 4 is a section on the line 4—4 of Fig. 3, the lower portion of the section being in a warped plane following two opposite passages.

50 I have illustrated my improved distributor in connection with a vertical tube condenser in which there are a plurality of tubes 10 within a shell 11, and connected to tube sheets 12. The upper tube sheet 55 operates with a peripheral wall 13 to form a vessel or chamber 14 for the cooling liquid,

said chamber being in open communication with the cooling tubes 10 which project through the tube sheet. The gas or vapor to be condensed is caused to circulate in or is 60 delivered to the chamber 15 within the shell and around the cooling tubes.

In connection with this condenser I employ a plurality of distributors, one for each of the tubes 10, and serving to deliver and 65 distribute the cooling water from the chamber 14 to the inner surface of the tube. Each distributor is in the form of a tubular member 16 having a lower portion 17 adapted to fit into the upper open end of a 70 tube 10 and provided with suitable stop means, as for instance a flange or shoulder 18 for limiting the downward or inward movement of the distributor, and supporting the distributor solely from the tube. The 75 lower portion 17 is of such diameter as to hold the distributor properly centered in the tube, and this portion, as well as the flange 18, is provided with a plurality of diagonal or helical grooves 19 each opening at its 80 upper end into the water chamber 14, and at its lower end into the tube. These grooves form passages for the cooling water and deliver separate streams of the water into the tube substantially tangentially. 85 By delivering the water in this manner the water is directed against the inner surface in such a way that it tends to remain in direct contact with the surface, and as the course of the current is modified by the 90 action of gravity, each stream will be effectively distributed about the entire periphery of the inner surface of the tube. By using a plurality of such passages constructed in 95 this manner, a uniform distribution of the water in the form of a thin film is secured and the water acts in the most effective manner to transfer heat from the fluid in contact with the outer surfaces of the tubes. 100 Each member 16 has a central passage 20 open at both ends.

The body portion of the member 16 above the flange 18, is preferably very much smaller than the tubes 10, so that its outer surface comes inside of the row of passages 105 19. Thus the passages may be easily machined as grooves along the full length of the larger diameter portion, and through the flange and the water may freely enter said passages when the members are in place. 110 This reduction in the diameter of the upwardly extending body portion is important

also, because it permits a far greater space between adjacent members in the chamber 14. Thus the chamber may contain a larger supply of water and the water may flow more rapidly and easily from the inlet to all parts of the chamber, and maintain a uniform head.

The members are of such length that the desired level of water may be maintained 10 in the upper vessel 14, and in case the water is delivered to the vessel at too rapid a rate, it may overflow through the central passages of the several distributors, and the level of the water in the vessel 14 will 15 thus be prevented from exceeding the predetermined height.

The distributors are supported solely by the tubes or the tube sheets, and are automatically centered within the tubes. Thus 20 the distributors may be readily removed to permit a rapid draining of the vessel, and may be as easily replaced. As the passages for the normal distribution of the water are in the form of shallow grooves, any 25 clogging or obstruction of the passages may be readily overcome by merely raising the distributor and flushing off the lower end thereof.

Having thus described my invention, what 30 I claim as new and desire to secure by Letters Patent is:

1. A distributor for the cooling liquid of a vertical tube condenser, including a tubular member having the lower part 35 adapted to be inserted within the open upper end of the condenser tube and to have a loose fit therein, and having a flange seating upon said tube end to support said member, said flange and the portion within the 40 tube having a plurality of registering helically disposed comparatively shallow long pitch grooves, and said member having a central passage serving as an overflow passage.

45 2. A vertical tube condenser having an upper tube sheet, a plurality of tubes projecting down therefrom and a wall coating with the tube sheet to form a vessel for cooling liquid above the tube sheet, said 50 vessel communicating with said tubes, said condenser being provided with a plurality of distributors within said vessel, each distributor having a central passage therethrough and having an outwardly extending 55 projection adjacent to the lower end, the portion below said projection extending into a corresponding tube, and said projection resting upon the upper end of the tube to support the distributor, said projection having spaced grooves, and the portion of the 60 outer surface of the distributor below the

projection having long pitch helical comparatively shallow grooves registering with the grooves in said projection.

3. The combination with a vertical tube 65 condenser having an upper tube sheet, a peripheral wall extending upwardly therefrom to form a vessel for cooling liquid and a plurality of tubes projecting downwardly from the tube sheet, of a plurality of distributors within said vessel, each including a lower portion extending into a corresponding tube, an intermediate portion of larger diameter than the tube, and seating at the upper end of said tube, and an upper portion of materially smaller diameter than 70 said tube to permit free flow of water in the chamber between the upper portions of adjacent distributors, each distributor having a central passage therethrough, and 75 passages through said intermediate portion and along the surface of said lower portion to deliver cooling water from said vessel to the inner surface of said tube.

4. A distributor for the cooling water 85 of a vertical tube condenser, including a tubular member having a lower end portion adapted to be inserted within the open upper end of a condenser tube, and a body portion of materially smaller diameter than 90 said lower portion, said larger lower portion having grooves in the outer surface and extending the full length thereof.

5. A distributor for the cooling water of 95 a vertical tube condenser, including a tubular member having an annular flange adapted to seat on the upper end of a tube, and means below said flange for holding the member concentric with the tube, a portion 100 of said member above the flange being of materially smaller diameter than the tube, and said flange having passages therethrough adapted to lead from the space outside of the portion above the flange to the interior of the tube below the flange.

6. A distributor for the cooling liquid of a vertical tube condenser, including a tubular member having the lower part adapted 110 to be inserted within the open upper end of a condenser tube, and having a plurality of helically disposed comparatively shallow grooves, the portion of said member above said grooves being of an external diameter less than the inside diameter of the row of grooves, whereby said grooves at their 115 upper ends terminate outside of said outer surface of the upper portion.

Signed at Carbondale, in the county of Lackawanna and State of Pennsylvania, this fourth day of January, A. D. 1923.

NICOLAI H. HILLER.
